REUBEN C. RUTHERFORD AND FERDINAND S. BARTRAM, OF NEW YORK, N. Y.

FILLING DEVICE FOR FOUNTAIN PENS OR TUBES.

SPECIFICATION forming part of Letters Patent No. 378,524, dated February 28, 1888.

Application filed April 29, 1887. Serial No. 236,589. (No model.)

To all whom it may concern:

Be it known that we, REUBEN C. RUTHERFORD and FERDINAND S. BARTRAM, citizens of the United States, and residents of 120 5 William street, New York, in the county of New York and State of New York, have invented certain new and useful Improvements in Filling Devices for Fountain Pens or Tubes, of which the following is a specification.

10 This invention is practically applicable to all forms or varieties of fountain pens or tubes used for these or other purposes which require to be charged or supplied partially or completely with any fluids that are to be kept, dispensed, used, retained, or discharged gradually, 15 instantly, or at intermittent periods in larger or less quantity, as circumstances may require.

It is well known that all or nearly all fountain-pens require in service the accompaniment of a glass or rubber filler or dropper—a separate, delicate, inconvenient, and otherwise objectionable instrument—which must be employed to supply them with ink as often as the pen-reservoir is exhausted.

25 We have provided a device which dispenses with this imperfect, annoying, and uncleanly article and enables the writer to utilize his case or pen-holder for this purpose, which is novel, simple, and effective, thus making it 30 possible and practicable for the user of any fountain-pen to which our invention is attached or applied to charge, discharge, and refill the same instantly wherever he may chance to be, or wherever ink in fluid form in 35 bottles or vessels may be found or produced.

It is difficult in practice to ascertain the precise volume of ink within or to determine with any approach to accuracy the proper quantity that may be injected into a rubber 40 pen case or reservoir by the old-fashioned methods, except by repeating the process until overflow occurs, as it is almost certain to do, and the hands and paper are soiled as the consequence. Our invention disposes of and obviates these and other objections and renders the act or operation of refilling a tube certain, 45 cleanly, and almost instantaneous.

The accompanying drawings, comprising fourteen different figures or diagrams, belong to and are made a part of this specification, and represent what we consider the best means of carrying out the invention.

Figure 1 is a lateral view of a fountain-pen complete in all its parts, with the exception of the cap or cover, (shown in Fig. 11,) for 55 which no claim for novelty is made; nor is any particular form of pen or writing or marking point or feed-bar or feed-tube herein described, as the invention is applicable to any or all forms or varieties that may be devised. 60 Fig. 2 shows the same construction of filling device after the process of filling has been completed and the pen is ready for service. Fig. 3 represents a slightly-modified form of the stop and cap-top, which may be adapted to 65 stylographic pens or to those represented in Figs. 1 and 2, as well as to the other figures in the drawings submitted. Fig. 4 shows another form—a floating globular stop—adaptable to either of the several forms herein 70 described, and represents the tube filled, showing the position of the globe with reference to the ink and tubular screw or plug when about to be closed. Fig. 5 represents a floating 75 balloon-shaped stop and its position in the ink, which is partially exhausted from the tube. Fig. 6 is a globular floating stop with a sectional cross-bar, W, or perforated wall, which 80 may be fixed within the tube to prevent the stop from dropping out when the pen and feeder are removed. Fig. 7 represents a caged 85 double-pointed globe-stop within the case and a floating tablet or disk-shaped stop, F', which operates the former, as will be hereinafter described. Fig. 8 shows a globular body form 85 of stop with a stem projecting from and attached to it; said stem also acting as an upward stop, in combination with the globe. This may be used in its present or reversed 90 position in the other tubes herein described. Fig. 9 represents a globular form of stop with a spine attached, which is the reverse of Fig. 3, and is held in position by a bracket, K, which may be attached to or hinged upon either 95 side of the inner surface of the tube. This tube is provided with a modified form of cap, which may be operated and adjusted by a screw-thread or by friction, and shows a rubber cushion or cork top, that may be provided to secure the closing of the perforation in the tube 100 with greater security. Fig. 10 shows a double-pointed globe-stop having a cap upon the tube similar to Fig. 9, but operated only by friction. The tube also contains a floating stop

of disk form, the operation of which will be hereinafter described. Fig. 11 is the cap or cover which protects the pen, and may be placed upon the upper end of the tube to 5 lengthen the case when the pen is in action. Fig. 12 represents the cylinder or cage, showing its perforations and containing a globular form of stop, which may be used in lieu of the ovoid conformation shown in Figs. 1 and 2. 10 Fig. 13 shows a bird's-eye view of a floating disk-shaped stop, which may be adapted to operate within the cylinder separately or below or above the same, in combination with the other forms herein described. Fig. 14 is 15 a lateral representation of the same, which may be constructed of any required length or circumference.

Similar letters of reference also indicate corresponding parts in all the figures where they 20 occur.

A is the case or tube; B, the feed-bar or feed-tube for supplying ink from the reservoir or tube to the pen; D, the pen; C, the cover; 25 E, the frame, cage, or cylinder containing the stop; F, the stop; G, the sliding or screw cap; H, the perforation in the lateral surface of the screw or plug and communicating with the longitudinal perforation in the same.

Referring to the construction, F, Fig. 1, is 30 a movable stop, of ovoid form, being elongated or partially or entirely pointed at the poles, which may be constructed of glass, cork, wood, rubber, or any suitable material, and having an automatic longitudinal and slightly lateral 35 movement, and resting loosely upon its poles within the chamber, cage, or cylinder E, which poles may project somewhat beyond or through the perforations at the top and bottom of the cylinder or cage. This cylinder may be constructed of hard or soft rubber or any suitable 40 material, and inserted within or be made integrally with the case or tube forming the perforations in the top and bottom heads or disks of sufficient diameter to permit the air and ink 45 or fluids to pass into and through it around the poles and body of the stop F when remaining in the position shown in Fig. 1. The form of these perforations should, preferably, conform to or correspond with the outlines or angles of 50 the poles of the stop F, so that when its position is changed by a proper or sufficient influx or efflux of air and fluids it will perform the office of a stop to the further admission of air or fluids operating in both directions, as will 55 be hereinafter more fully described.

G is a tubular stem, of wood, hard rubber, or other analogous substance, having preferably a screw-thread cut upon its outer surface corresponding to and moving within a threaded 60 orifice at the upper extremity of the tube, as shown in Fig. 1. It is provided with a head, by which it may be moved inwardly or outwardly, as occasion may require.

H is a small lateral perforation in this stem 65 communicating with the longitudinal bore of the same. The head of this tubular screw is

conformed upon its under side to correspond with the surface of the upper end of said tube, making the connection air-tight when closed or turned down to its farthest limit, and the 70 reverse when turned backward or upward sufficiently to expose the perforation H just described and represented in this figure.

In Fig. 2 the tube is represented as having been charged or filled with ink, and is ready 75 for service. The stop F, as will be noticed, has closed the perforation in the lower head of the cylinder E, partly by gravity and positively by the downward pressure of the screw G upon and around the upper pole of the stop 80 F, with which it forms a close-fitting connection, thus producing a triple combination for the effectual closing of the upper end of the tube. Still the automatic action of the stop alone will close it for ordinary purposes, as 85 will be hereinafter described.

In Fig. 3 a modified form of stop is adapted to cases used for stylographic pens or points whenever the tube requires ventilation at the top while in action. The stop is of more globular form, having but one pole, which may be used, however, in Fig. 1 in its normal or reversed position with equal effect. In this figure (3) the lower head of the cylinder is provided with two perforations, through which 90 the ink rises and floats the stop against the upper head of this cylinder and closes the tube by upward action only. The orifice in the tube in this figure is shown at x, and is opened or closed by means of the sliding cap G. 95

The construction of Fig. 4 differs from the preceding ones in dispensing with the cylinder or cage E and substituting a globular floating stop which operates perfectly under ordinary conditions.

In Fig. 5 we provide a balloon-shaped stop to produce the same results.

Fig. 6 shows a construction in which nearly the entire capacity of the reservoir or tube may be utilized, a tubular stem being affixed 110 to the upper extremity of the case and provided with a tightly fitting or closing screw or sliding cap, as may be preferred. We also provide a single perforated disk, (shown at W,) which may be constructed within the tube or 115 adjusted below the stop to close by contact with the ball or stop, and which also prevents the same from dropping out.

The construction of Fig. 7 represents a stop and cylinder similar to those of Figs. 1 and 2, 120 the stop being somewhat more globular in form, and being and acting in combination with a floating disk-shaped stop, (shown at F'), which rises with the fluid until it comes in contact with and raises the caged stop F, closing the 125 upper perforation, and also the lower one by contact with the lower surface of the cylinder, forming a most effective device for this purpose. The perforation in the tube is shown upon one side of the solid screw-stem, and is 130 closed by the cap G when turned down to its seat upon the outer extremity of the tube.

In Fig. 8 we have provided a globular form with a stem attached, having a stop projecting at right angles with its lower terminus, and designed to move through a disk having a single perforation and acting as a stop in both directions. This form may also be reversed with good results.

The construction of Fig. 9 shows a globular form with a spiral attachment pending downward through a rest or bracket attached to or hinged upon one side of the inner surface of the tube, which prevents it from dropping out. The tubular top of the case is closed by a cap, G, having a rubber or cork packing or cushion. (Seen at *.)

The construction of Fig. 10 shows a similar cap with two separate perforated disks, which may be adjusted at any required distance apart, and may also be operated by a floating disk-stop, F', having a flat or oval surface, and acted upon by air and fluids in the same manner as shown in Fig. 7.

The operation of charging or filling the tube may be described as follows: Reverse the screw-cap G from the position shown in Fig. 2 until the perforation of the screw at H becomes apparent, as seen in Fig. 1. Place the opposite end in a vessel of ink or fluid sufficiently to immerse the opening. Place the lips over the perforation H and exhaust the air by suction. As the air is exhausting, the fluid rushes upward, replacing the vacuum floating the stop and carrying it upward against the perforation in the upper head of the cylinder, closes it to the further passage of the fluid into the chamber above the cylinder, and prevents it from reaching the lips or mouth. A distinct sensation is felt when the stop strikes the upper perforated head of the cylinder, which evidences that the tube is filled to this point. As the lips are withdrawn, the stop, by gravity and the reflucent tendency of the ink or fluid, drops to the lower perforation in the cylinder and closes this in like manner. Then the cap may be screwed down, and the pen or tube is ready for service. The entire operation is almost instantaneous.

It is evident that many modifications may be made without departing from the principle or sacrificing the advantages of this invention. Therefore we do not desire to limit ourselves to the precise or rigid construction of the few forms herein described. The conformation and construction of the tubes, stops, cages, cylinders, screw, and sliding caps and ventilators may be varied. We may dispense with the two-pointed stop in Fig. 1 and substitute any of those in the other tubes or any modifications of the same. We may transpose, invert, or combine any of the globes, balls, or stops named herein, adopting other forms of stops, which may be spheroids, oblate, or prolate, ellipses, concaved, or convexed. We may operate the screw-caps in the figures where they occur by friction only, or adapt screws to the friction-caps herein described. In Fig. 1 we may tip the lower part of the tubular screw

with soft rubber to form a more positive or more perfect fitting seat, and this may be adapted to the other forms also.

We may construct the stops of hollow material partially or entirely, or in any manner to adapt them more perfectly to the purposes expressed, and to raise or float the upper portion of them, as far as may be desirable, above the surface of the fluid to preclude the liability or possibility of the liquid from contact with the mouth under normal or abnormal conditions. We may also use the floating stops within or above the cage or cylinder when practicable, and arrange and combine them all so as to form single, double, or triple stops in either or both directions. The various forms of stops may also be used with or without the tubular screw or sliding or friction caps G described, and the cylinder perforations may be of any shape to conform to the poles employed.

We claim as our invention—

1. In a fountain pen or tube, a self-filling device consisting of a cylinder having perforated heads adjusted within the tube or case, in combination with a movable stop of ovoid conformation within said cylinder, said stop being provided with poles sufficiently elongated to project through said perforations, and around which poles air and ink or fluids may pass to operate to open or to close either of said perforations by the automatic action of said stop, produced by contact with or displacement of air and ink or fluids within said tube, substantially as in the manner hereinbefore described, and for the purposes specified.

2. In a fountain pen or tube, a self filling, retaining, and dispensing device for fluids, consisting of a cylinder having perforated upper and lower heads adjusted within the tube and incasing a movable stop of globular, oval, or other suitable or variable body or form, from which extend in opposite directions two arms or poles sufficiently elongated to project through said perforations, and around and between which poles and perforations air and fluids may pass above or below said cylinder, and may be restricted and excluded from further passage by the automatic reciprocating movement of said stop within the cylinder when operated by the filling of said tube by immersion or by exhausting the air therefrom.

3. In a tube, a floating stop partially immersed and moved by the fluid, in combination with a tubular opening and closing screw or plug at its upper end, having its lower orifice conformed to the periphery of the stop at their points of contact for the purpose of closing the upper extremity of the tube and preventing the fluid from rising above the upper surface of the stop when being charged or filled by immersion or suction, and constructed substantially as hereinbefore described.

4. In a fountain pen or tube having a perforated top or cap, one or more perforated disks adjusted within the tube, in combination with one or more floating stops below,

above, or between said disks, all jointly or separately operating in the manner described, and for the purposes specified.

5. A fountain-pen consisting of a tube, a pen, *d*, feed-bar *b*, cage *e*, containing the stop *f*, in combination with the tubular screw *g*, for the purposes declared, all constructed and arranged for joint operation substantially as hereinbefore described.

Signed at New York city, in the county of 10 New York and State of New York, this 28th day of April, A. D. 1887.

REUBEN C. RUTHERFORD.
